UNITED STATES PATENT OFFICE

JOHN GOOD, OF GARDEN CITY, NEW YORK, ASSIGNOR TO AUTOMATIC MOTOR STOP AND START, INC., OF NEW YORK, N. Y., A CORPORATION OF NEW YORK

ENGINE-STARTING SYSTEM

Application filed June 29, 1928. Serial No. 289,314.

The object of the invention is to improve the engine starting systems of automobiles and includes the organization of the starter mechanism in such a way that the physical effort required of the driver to set such mechanism in action is opposed by a counterpressure while the engine is firing or is being driven by the momentum of the automobile, thereby providing certain advantages hereinafter made to appear. The invention also includes improved starter mechanism particularly suited for obtaining the result stated and so organized as to guard against accidental operation thereof when the engine is firing, or being driven as stated, as well as to provide other advantages having to do with simplification and improvement of the starting process, all as herein described and exemplified in the accompanying drawings.

Fig. 1 shows part of a conventional automobile power plant having the invention applied,

Figs. 2 and 3 larger scale views of one form of starter switch,

Figs. 4 and 5 the application of the invention to a different type of starting mechanism,

Fig. 6 an end view of the showing of Fig. 5, certain elements being omitted for clearness, and

Fig. 7 illustrates a modified form.

The power plant illustrated in Fig. 1 includes an engine 1 and a carburetor 2 connected therewith by intake 3. As will be understood, the connection of the engine and running gear is controlled by a clutch enclosed in housing 4 and operated by a pedal lever 5 which extends through the dash into the operator's compartment. The engine is started by means of an electric motor 6 which when energized is automatically connected with the engine as by a so-called Bendix or self-engaged drive. The circuit of the motor, represented by cables 7, includes a storage battery (not shown) and an operator's switch 8 which may occupy its customary position on the dash but which is preferably located, as shown, for operation by an abnormal stroke of the clutch lever i. e. by a further throw of the lever after the same has been moved to disconnect the engine and running

gear. An arrangement of this general character is illustrated and described in my co-pending application Ser. No. 272,559, filed April 24, 1928.

Referring to Figs. 2 and 3 which illustrate the preferred form of one type of starter switch unit, a casing 9 encloses a pair of insulated contacts 10 which are connected with binding posts 11. One side of the casing has an extension 12 for the switch plunger 13 which carries the bridge piece 14 at its lower end and at its upper end is riveted to a cap 15 which telescopes over extension 12. A second or cushion cap 16 is fitted over cap 15 and normally urged away from it by spring 17, outward movement of cap 16 being limited by the in-turned lips 18 confined to slots 19 in cap 15. Switch spring 20 holds the plunger in its open-circuit position. At the other side of casing 9 a block 21 supports a cup member 22 having its outer end closed by a flexible diaphragm 23 and cover 24. The enlarged head 25 of a piston member or stem 26 engages the diaphragm, the stem 26 being longitudinally movable in block 21 and terminating adjacent the end of the switch plunger. The switch may be supported by bracket 27 secured directly to the steering column or otherwise mounted to suit the conditions in hand. As shown it lies in the path of the clutch pedal lever at or beyond the limit of its normal stroke, when used for declutching but in position to be engaged and depressed by such lever on a further depression, thus to close the circuit of the starting motor which, in the case in hand, is all that is required to crank the engine.

The diaphragm chamber is subject to the suction of the engine by way of pipe 29 connected to the intake 3 above the throttle 30. While the engine is being cranked by the starting motor, the suction effect in the intake is too feeble to produce an appreciable operation of the diaphragm 23 but as soon as the engine fires and becomes self-actuating the immediate increase of the intake suction sucks in the diaphragm to the position shown, causing the stem 26 to push the switch plunger to its open position overcoming such pressure as the driver normally uses for closing the starter

switch and such switch is accordingly opened, bringing the starter motor to rest. The upward movement of the switch plunger under the operator's foot serves to inform him that the engine is started, a fact not always easily determined, particularly in traffic where the noise of the surrounding vehicles makes it difficult to hear if the engine is running, and obviously the immediate opening of the switch saves the battery, by limiting the discharge period to that actually required to start the engine.

When the engine is running, which term is intended to include the driving of the engine by the vehicle at all speeds above that corresponding to idling as well as normal combustion operation, the engine suction maintains the diaphragm and its stem in their switch-opposing position (Fig. 2), so that cap 16 and cap 15, sustained by the suction, constitute a bumper device which serves to limit the normal clutch stroke, thereby avoiding inadvertent closing of the starter switch.

It will be apparent, therefore, that I have provided a starter switch adapted to be manually closed and automatically opened in opposition to the closing pressure. By reason of this fact spring 20 need only be strong enough to hold the plunger in its open-circuit position, when the engine is at rest, and accordingly the switch closing movement of the clutch lever to start the engine is subject to practically no resistance other than the usual clutch spring, the starting act being thus accomplished more easily and with less pressure than in existing starter systems where the switch incorporates a heavy spring. Spring 17 is stronger than spring 20 and together with cap 16 forms a cushion against which the starter switch is held closed, it being easier to maintain a steady foot pressure on a yielding switch than on a rigid one. Ordinarily therefore spring 20 yields when pressure is applied to cap 16 and spring 17 yields, as a cushion, only after the switch has been closed.

In Fig. 2, I have also shown a safeguard against the possibility that, under certain conditions, the suction developed by the cranking of the engine, prior to its firing, may be sufficient to operate diaphragm 23. The larger the diaphragm the greater is its tendency to respond to cranking suction. As illustrated, the device comprises a reed valve 31 which overlies a hole 32 in the wall of the diaphragm chamber and is so sprung that under any degree of suction likely to be produced by electric motor rotation of the engine, it vents the chamber to atmosphere but is weak enough to be sucked closed by the stronger suction developed as soon as the engine fires, so that when the engine becomes self-actuating, hole 32 is closed and the full suction effect applied instantly to the diaphragm to operate the same in the manner described.

In Figs. 4, 5 and 6 the invention is shown

applied to starting mechanism of the so-called "positive-type" which is well-known and in which a part of the starting mechanism is moved by the operator, to connect the motor to the engine, coincidently with the closing of the starting circuit. The starting motor 33 drives a countershaft 34 on which slides a driving unit consisting of a clutch collar 35, which is splined to shaft 34, and a loose, overrunning starting pinion 36 which is connected to the clutch collar by drive spring 37. The collar is embraced by yoke 38 rigidly secured to rock shaft 39 (Fig. 6) which is moved as hereafter described to slide the driving unit from the idle position shown in Fig. 4 to the driving position shown in Fig. 5 in which pinion 36 is meshed with the fly-wheel teeth 40. The design and mode of operation of this mechanism is well understood in this art.

As in the form of Fig. 1, the starter is shown located for operation by the clutch pedal lever and to this end lever 5 carries a heel-piece 41 which has a pin and slot connection with one end of the operating rod 42, the other end being connected to crank pin 43 bolted to arm 44 which is secured to rock shaft 39.

Because of the relatively long stroke which the sliding of the drive unit entails, as compared with that of the switch plunger, the starter switch and the suction-operated control may be mounted separately, as shown, the latter preferably consisting of a suction cylinder and a piston having a stroke suitable to accommodate this larger movement. For this purpose cylinder 45 is secured to the starter motor casing and connected with the intake by pipe 46 as in the form of Fig. 1. The piston rod 47 of piston 48 is adapted to be engaged by the upper end of arm 44 and motor switch 49, also secured to the motor casing, is adapted to be engaged by a thrust screw 50 carried by arm 44. This switch 49 may be similar to that above described, omitting the suction chamber and diaphragm stem, or it may be any other form of switch normally held open by a spring.

When arm 44 and shaft 39 are rocked by the depressed clutch pedal, from the position of Fig. 4 to that of Fig. 5, the drive pinion 36 is engaged with the flywheel teeth, as above described, and switch 49 is closed by the engagement of screw 50 therewith. The timing of the closure of the switch relative to the engagement of the pinion and flywheel is accomplished by the adjustment of screw 50 and is preferably such that the pinion is in substantial driving engagement with the flywheel teeth or ready to enter them, before the motor is energized. As soon as the engine fires, pinion 36 over-runs its shaft as will be understood, and the increased suction of the engine incident to its self-actuation pulls piston 48 from the left hand to the right hand end of cylinder 45 so that the

piston rod, engaging the upper end of arm 44, pushes the latter back to the position of Fig. 4, against the pressure imposed by the operator's foot, thereby disengaging the starting motor from the engine and permitting the switch to open under the influence of its spring.

In Fig. 4 the full line and dotted line positions of the clutch pedal represent what may be termed the normal declutching stroke, throughout which pin 51 merely slides up to the other end of slot 52. At this point, if the engine is running under its own power, arm 44, is opposed by piston rod 47 (Fig. 4) sustained by the intake suction acting to hold the piston in the position shown, thereby constituting a yielding bumper-limit device and serving to guard against accidental operation of the starter but permitting such operation when intended. If the engine is at rest, movement of the clutch lever beyond its dotted line position, acts through pin 51 and rod 42 to rock arm 44 and shaft 39 with the effect already described.

If the operator withdraws the clutch pedal before the engine fires, the initial part of its return movement is without effect on the starting mechanism since the lever will not pull the arm 44 back to its normal position until pin 51 strikes the other end of its slot. The switch spring alone is ordinarily not strong enough to withdraw the driving unit against the friction of the then engaged pinion and flywheel teeth, so that during the time required for the pin to reach the end of its slot, the starter mechanism remains in action. The effect is thus automatically to increase the cranking period by the time interval requisite for the pin to reach the end of the slot and so lessen the possibility of the engine failing to start as a result of only a momentary pedal depression. The pin and slot connection is so organized that the pin engages the end of the slot positively to return arm 44 and render the starter inoperative before the clutch lever reaches its clutch-engaging position, so that there is no danger of the engine and running gear being connected while the starter is in operation.

The spring 53 appearing in Figs. 4, 5 and 6 is employed to assist the return of the arm 44 after it has been started back by the piston rod. It is connected between a fixed stud 54 and the end of pin 43 (Fig. 6) and holds practically a dead center position with relation to pivot axis 39 when the arm is in its circuit closing position (Fig. 5) so that it exerts little or no restoring pressure at this time but is available to throw the parts back smartly as soon as started. Obviously this spring could, if desired, be so connected as to restore the parts immediately on removal of the foot pressure. It will be observed that the resistance which it opposes to the switch closing movement of the clutch pedal de-

creases as such movement progresses, that is to say, the spring moves towards its dead-center position and thus does not materially increase the effort necessary to engage the pinion and fly-wheel teeth and close the starter switch. In any event, and whether or not the return spring 53 is used as preferred, or not at all, the piston rod acts to exert a counter-force in a direction against the pressure exerted by the driver as soon as engine becomes self-actuating, and thus guards against inadvertent actuation of the starter mechanism while the engine is running, as in the form first described.

Within the principle of the invention, it will be seen that the particular means whereby the counter-force is produced and made effective on the starter mechanism is not vital to the attainment of the general object of the invention, since that object is merely to exert a suitable counter-force when the engine is running, which force preferably (as in the forms of the invention here illustrated) becomes effective immediately upon the starting of the engine thereby providing the further advantage that the operator is definitely apprised of the fact that the engine is running. The counter-force or increased resistance by which closure of the starting circuit is opposed while the engine is running may be derived from or rendered effective by any of the variable functions of the engine, other than the intake suction, and such as have been heretofore proposed for the control of starting systems; that is to say, the pressure of the cooling, oiling or exhaust systems, or electrical pressure from the engine generator, all of which attain a definitely higher value when the engine is firing than when it is simply being cranked by the starting motor. The utilization of the engine suction as the source of the counter-force offers particular advantages having to do with convenience, cost of manufacture and reliability of action as has already been made apparent, on which account it is preferred.

The suction effect in the intake, with the engine running, is ordinarily ample for the operation of the invention, but in certain conditions it is possible that proper functioning may be interfered with. For example, if the driver opens the engine throttle at a time when the diaphragm or piston is intended to be exerting its counter-pressure, such opening causes a temporary reduction in the intake suction, that is to say, until the engine accelerates in response to the throttle opening. This is only a matter of a second or two but the reduction may be sufficient to destroy the effective bumper function so that without increasing the effort with which the clutch lever is being held down, the driver may inadvertently depress it further and close the starter switch, the engine being in operation. Fig. 5 illustrates one means of overcoming this objection.

It consists of a valve box 55 inserted in the suction line with its interior 56 open to the intake by way of pipe 57. The suction effect of the engine is transmitted to pipe 46 by way of passage 58, vent 60 and ball or like valve 61 serving to relieve the cylinder of the cranking vacuum and to close as soon as the engine fires. This valve operates in a similar manner to the reed valve 31 shown in Fig. 2. In addition, however, passage 58 is controlled by a ball or other valve 59 so loaded as to resist a vacuum of say four or five inches of mercury in the intake but to open under greater vacuum. This loading is ample to ensure prompt closing of passage 58 to maintain the vacuum condition of cylinder 45 under the temporary low vacuum condition above referred to. When the engine comes to rest the vacuum condition of pipe 46 and cylinder 45 is relieved by leakage through a bleed or by-pass 62 around valve 59 so that ball 61 is permitted to fall and so restore the system ready for the next starting operation. By varying the size of the by-pass any desired delay can be interposed between the failure of the intake suction and the re-setting of this device to permit the engine to be restarted and a delay of a second or two may be desirable to avoid the possibility of the cranking mechanism being again rendered active before the engine has actually come to rest.

It will be noted that except for the small bleed or by-pass 62 there is no leakage from atmosphere to the intake by way of passage 60 unless the intake suction exceeds the four or five inches of mercury required to lift ball 59. This is important in that under low vacuum conditions, as in cold weather when the cranking speed is low and when with the choke closed a suction of only about two inches of mercury is developed, the presence of vent 60 might be sufficient to interfere seriously with or even prevent the engine starting. Ball 59 therefore serves not only to close off cylinder 45 but also, to delay the action of vent 60 until the engine suction is high enough to be insensible to it. A further function of ball 59 is to prevent the pressure of a back-fire from being transmitted to piston 48.

In the modified form of Fig. 7, an extension of the switch plunger 13 engages the short arm of lever 63, pivoted at 64, the longer arm of the lever engaging the end of diaphragm stem 26. The other elements will be recognized from the description of the form of Fig. 2. By suitably proportioning the lengths of the lever arms the mechanical advantage of the diaphragm and stem can be made as desired, so that the size of diaphragm or piston necessary to produce any given switch-opposing resistance may be kept within reasonable limits, even though the suction which the engine develops is relatively low.

I claim:

1. In an automobile the combination of an

engine, a clutch lever, a starter and a circuit therefor having a switch organized for closure by an abnormal declutching movement of said lever, and means operated by a variable function of the engine to open said switch against the closing pressure applied by said lever. 70

2. In an automobile the combination of an engine, a starter and a circuit therefor having a switch adapted for manual closure and means responsive to the firing condition of the engine for applying a counter-force to the closing pressure manually applied to said switch. 75

3. A starting system comprising the combination of an engine, an electric starting motor therefor, a motor circuit having a switch adapted to be manually closed to start said motor and means operated by a variable function of the engine adapted to overcome the manually applied switch closing pressure. 80

4. In an automobile the combination of an engine, a starter, a circuit therefor, a switch in said circuit including a movable contact-making member, a spring urging the same toward its open position and engine-operated means for moving said member towards said open position. 85

5. In an automobile, the combination of an engine, a starting motor, a starter circuit, a switch therefor including a contact-making member, and means controlled by a variable function of the engine producing two degrees of resistance to the circuit-closing movement of said member. 90

6. In an automobile the combination of an engine, a starter circuit, a switch therefor having an operating member adapted for manual depression, two means for returning said member and means whereby only one of said means is active when the engine is dead. 105

7. In an automobile, the combination of an engine, a clutch lever, a starter having a controlling switch adapted for operation as the result of an abnormal declutching movement of said lever and means responsive to the firing condition of the engine acting to return said lever substantially to the limit of its normal declutching stroke. 110

8. In an automobile, the combination of an engine, a clutch lever, starter mechanism including contacts adapted to be closed by an abnormal declutching stroke of said lever, a plunger member adapted to be depressed by such abnormal stroke and engine-operated means for returning said plunger with sufficient power to overcome the ordinary pressure of said lever. 115

9. In an automobile, the combination of an engine, a clutch lever and mechanism organized for operation by an abnormal declutching stroke thereof, including a bumper member located in the path of the clutch lever and opposing a yielding resistance to movement thereof and means operated by a vari- 125

able function of the engine to increase said resistance.

10. In an automobile the combination of an engine, a clutch lever and starter mechanism located for operation by an abnormal de-clutching stroke thereof including a bumper member limiting the normal de-clutching stroke and automatic means for varying the resistance opposed by said member to lever movement beyond such limit according as the engine is or is not running.

11. In an automobile the combination of an engine, a clutch lever, a device to limit the normal de-clutching stroke thereof and suction means operative to increase the limiting resistance opposed by said device in response to running of the engine.

12. In an automobile the combination of an engine, a clutch lever, a starter mechanism located for operation by an abnormal de-clutching stroke including a switch, means operated by the engine to cause the opening of said switch and control means permitting or preventing operation of said first means according as the engine is or is not running.

13. In an automobile, the combination of an engine, a cranking motor and a starter switch therefor, manual means for closing said switch, means operated by a variable function of the engine to positively open said switch when the engine is firing and a device to render said means ineffectual while the engine is driven only by said cranking motor.

35 14. In an automobile the combination of an engine, a fuel intake thereto, a cranking motor and a starter switch therefor, manual means for closing said switch, means operated by intake suction to cause the opening of said switch when the engine is firing and a device to render the intake suction substantially ineffective on said switch opening means during cranking of the engine.

15. In an automobile the combination as set forth in the preceding claim, in which said device comprises a valve adapted to be closed only by the suction incident to engine-firing.

16. In an automobile the combination of an engine, intake and a throttle controlling the same, engine-starting mechanism adapted for manual operation, means operated by the intake suction for exerting a counter-force against such manual operation and means preventing decrease of the suction which acts on said means when the throttle is opened.

17. In an automobile, the combination of an engine, a clutch pedal, a starter system having a controlling member so related thereto as to be operated only by an abnormal depression of the pedal and including a switch and starter pinion respectively closed and brought into engine-cranking position by the use of said member, a device adapted

to exert a counter-pressure on said member sufficient to cause the opening of said switch and the return of said pinion and means whereby said device is operative only when the engine is running.

18. In an automobile, the combination of an engine, a starter system having a controlling member to be manually moved to its engine-starting position, said member adapted to retain such position independently of manual pressure and means for returning the member to normal position when the engine fires.

19. In an automobile the combination of an engine, a starter system including a starter circuit and a starter pinion adapted to be automatically engaged with the engine to drive the same when the circuit is energized, a member to be manually moved to close said circuit and means to return said member against its closing pressure in response to engine-firing.

20. In an automobile the combination of an engine, a starter system including a controlling member to be manually moved to engine starting position, a switch and starter pinion respectively closed and brought into engine-cranking position by such movement of the controlling member and means responsive to engine-firing to restore said switch and pinion to their inoperative positions.

21. In an automobile, the combination of an engine, a controlling member for manual operation to start the same and means for exerting a counterforce against such manual operation in response to running of the engine, including a lever adapted to increase the mechanical advantage of said counter-force and transmit the same to said controlling member.

22. In an automobile, the combination of an engine, intake, a starter arranged for manual manipulation to start the engine, a suction device organized to oppose a counter-pressure to such manual manipulation when the engine fires, a suction line connecting said device with the intake, and a valve in said line closing towards said device and loaded so as to close when the intake suction falls below a predetermined value.

23. The combination set forth in the preceding claim including means effective after a predetermined interval to relieve the vacuum condition resulting from the closure of the valve, said means comprising a restricted inlet to said line intermediate the valve and the suction device.

In testimony whereof, I have signed this specification.

JOHN GOOD. 125
